ATTACHMENT FOR TYPEWRITING MACHINES

Paul Hegnauer, Berlin, Germany, assignor to Ruf-Buchhaltung Aktiengesellschaft, Zurich, Switzerland, a corporation of Switzerland

Application January 6, 1943, Serial No. 471,521
In Switzerland March 30, 1942

10 Claims. (Cl. 197—128)

The present invention relates to attachments for typewriting machines, particularly adapted to facilitate the rapid and accurate locating of forms for instance of an individual account sheet over a ledger sheet and over a record sheet placed on the platen of the paper carriage in such a position that simultaneously entries may be written on three forms.

One object of the invention is to provide a contrivance for a type writing machine which will enable one or more forms to be quickly and accurately and individually positioned above the record sheet fastened on the platen in such a manner that the lines of all the superposed forms on which the entry is to be written are exactly in line one above the other.

A further object of the invention consists in the provision of a device of the said type which allows the partial replacement of the forms and the recollation of the same in a speedy manner.

To the accomplishment of these objects and others as will hereinafter appear, an embodiment of the invention is illustrated in the accompanying drawings.

In the drawings the device is shown in a diagrammatical manner:

Fig. 1 is a front elevation of the carriage of a typewriter, parts being broken away, only those parts being shown which are essential for the explanation of the invention.

Fig. 2 shows parts of the device in a plan view.

Fig. 3 is a side elevation, parts being shown in section.

Fig. 4 shows an actuating rack in side elevation and

Fig. 5 a set of arresting bars with actuating levers.

Figs. 6, 7, 8 and 9 are sections on the lines VI—VI, VII—VII, VIII—VIII, and IX—IX of Fig. 5.

Fig. 10 is a detail of construction on a larger scale.

Fig. 11 is a side elevational view of a hand operated sheet feeding device.

On the carriage 1 of a type writing machine a horizontal bar 2 is fastened on which a chute 4 is adjustably mounted and held by a set screw 3 (Fig. 3). In the chute 4 a partition wall 5 is arranged in such a manner that two guide ways for two sheets are formed. On the side wall of the chute two shafts 9, 10 are rotatably mounted. On each shaft 9, 10 two spur wheel, 7, 1 and 8, 8 are mounted. The teeth of each pair of the spur wheels 7, 1 and 8, 8 project through the guide ways into a window 6 of the wall 5. The shaft 9 drives

by bevel gears 11, 13 (Fig. 2) a shaft 15 and shaft 10 by bevel gears 12, 14 a hollow shaft 16 loosely mounted on shaft 15. The shaft 15 carries a spur wheel 17 and the shaft 16 a spur wheel 18. The spur wheels 17, 18 engage toothed racks 19, 20 respectively. The racks 19, 20 run parallel each other, they are slidably mounted in the carriage 1. Each rack stands under the action of a coiled spring 1 (Figs. 2, 4) one end of which is fastened to the rack and the other to the end wall of the carriage. At the centre of the back wall of the frame of the type writing machine a casing 21 is arranged (Figs. 3, 4 and 5). In said casing 21 a row of vertical bars 22 (Figs. 4, 5, 7, 9) are arranged. The bars 22 run in a vertical direction, they are at equal distance apart and each of them may be brought in the path of noses 34, 35 of the rack 19, 20. Each bar 22 stands under the action of a spring 32 and may be moved upwardly against the action of said spring 32 by a lever 29 pivoted in the frame of the machine. One end of said lever 29 is provided with a button 28 the other end with a cross pin 31 engaging a notch 36 at the lower end of bar 22. The buttons 28 of all the levers 29 and the bars 22 are arranged in rows in front of the keys of the type writing machine (Fig. 2). Each bar 22 is provided with a projection 22a extending below a lever 43 (Figs. 5—9) rockably mounted on the wall of casing 21. The lever 43 co-operates with a two-armed lever 51 pivoted at 52 to the back wall of casing 21. One arm of lever 51 is held in contact with the lever 43 by a spring 53, the other arm ends in a pin 36 engaging a bore of a bar 23. The latter is slidably mounted on a stud 40 of a link 40a pivoted at 40b to the wall of the casing 21, the upper end projects through a slot of said casing and may be made to co-operate with the two racks 19, 20. In the position shown in Figs. 4 and 7 the bar 23 retains the rack 19 in its position against the action of spring 1. The stud 40 projects through a slot in the bar 23 in such a manner that the same may be lifted but vertically by the levers 43 and 51. Moreover the bar 23 may be turned on the pin 36 to bring the upper end thereof in or out of the path of the two racks 19, 20 so that they may be set by the action of the spring 1. In the position of rest shown in Fig. 8, the upper ends of two levers 39 pivotally mounted on the side wall of casing 21 are held in contact with the pin 40 of link 40a and with a pin 41 of the casing 21 by a spring 38. In this position the bar 23 locks the rack 19. To bring bar 23 either in the path of rack 20 or else in or out of the path of both racks 19, 20 the bar 23 is turned

on pin 36 by a rod 37. The rod 37 ends near the keys 28 and may be moved manually.

On a pin 42 of the lever 43 a bar 24 is rockably mounted. The bar 24 takes part of the movements of said lever 43 and may be turned on pin 42 by a rod 45. One end of rod 45 ends near the keys 28 and the other end is connected by a member 46 with the lower end of the bar 24. The member 46 is provided with two slots 48 into which project two guide pins 47 allowing but a limited movement to the member 46 and to bar 24. A pawl 49 is held in engagement with a toothed portion of member 46 by a spring 50. The pawl 49 secures the bar 24 in its position. The upper end of bar 24 cooperates with two pawls 25, 26 engaging the racks 19 and 20 respectively and held in engaging position by spring 27. If bar 24 is lifted by lever 43 it strikes against one or the other pawl 25, 26 (Fig. 6) according to the position into which it has been brought by rod 45.

The racks 19, 20 may be shifted step by step and by a hand lever 54 (Figs. 2 and 11). The lever 54 is pivoted to the frame of the carriage 1. One arm 55 of lever 54 acts on a bar 56 (Fig. 11), slidably mounted on the said frame. The bar 56 operates an angular lever 57 pivoted at 58. One arm 59 of lever 57 engages a horizontal slot 60 of a member 61 rockingly mounted on a pin 66 projecting through a vertical slot 65. The member 61 carries a pawl 62 which is held in engagement with the spur wheel 17 by means of a spring 64 attached with one end to the member 61 and with the other to the frame of the carriage 1. By operating the hand lever 54 once, the pawl 62 shifts the spur wheel 17 by one tooth. The pawl 25 is withdrawn from the rack 19 the latter allows the wheel 17 to rotate. The rotation of the wheel 17 is transmitted to shaft 9 and the spur wheels 7, 7 move the sheet 68 (Fig. 3) in the chute by one line. The perforations 67 are rectangular, the teeth of the spur wheels have a good bearing on the edges of the said perforation. The locating device may be used as follows to place two different sheets above a third sheet which is held on the platen of the carriage by well known means. The two sheets are introduced in the chute 4 one on each side of the partition wall (Fig. 3). The lower edges of both sheets rest on the teeth of the spur wheels 7, 7 and 8, 8. The carriage 1 is brought to its end position, its actuating spring 50 is thereby tensioned. During this movement of the carriage 1, the racks 19, 20 are held stationary by the bar 23 engaging the noses 34, 35 of said racks. The springs F are tensioned. The rod 45 is actuated and the upper end of bar 24 is positioned below the pawl 26 (Fig. 4). The key 28 corresponding to that line of the sheet 68a on which an entry is to be made is now pressed. The corresponding bar 22 is lifted by lever 29 and rocks thereby lever 43 and therewith lever 51. The latter draws bar 23 downwardly, while bar 24 is moved upwardly far enough to bring the pawl 26 out of engagement with rack 20 (Figs. 4, 6). The bar 23 has in the meantime freed the rack 20 and the contacting spring f draws the rack 20 until its nose 35 strikes against the upper end of bar 22 which has been set by the key 28. The rack 19 remains in its position, it is held by the pawl 25. The rack 20 turns the spur wheel 18 and therewith shaft 16, the bevel gears 12, 14 and shaft 10 with the spur wheels 8, 8. The teeth of said wheels 8, 8 enter the perforations 67 and the sheet 68a is moved in the chute by the distance of two consecutive lines. This operation may be repeated until that line of sheet 68a

is above the line of the form held on the plate on which the entry is to be written.

To locate the sheet 68 the rod 45 is again set to bring the upper end of bar 24 below the pawl 25. The key 28 corresponding to that line of sheet 68 on which an entry is to be written is pressed and the corresponding bar 22 is moved in the path of nose 34 of the rack 19. The performance described with reference 20 is repeated, the spur wheel 17 is rotated and transfers its movement to the spur wheels 7, 7. The sheet 68 is drawn downwards.

The carriage 1 travels on the frame while the entry is made in the well known manner. Having the entry written the bar 23 is brought to that position in which its upper end projects in the path of both noses 34, 35 of both racks 19, 20. While the carriage 1 is brought back to its initial position the racks 19, 20 are arrested by the bar 23. The spur wheels 17, 18 roll on the racks 19, 20 and turn the gears 7, 7 and 8, 8. The sheets 68 and 68a are moved upwards in the chute and may be taken out by hand. If it is not desired to withdraw the sheets 68, 68a the bar 23 is brought out of the path of both noses 34, 35.

By shifting the carriage to its initial position by the hand lever 54, the platen with the sheets 68, 68a are simultaneously moved by a line.

The side walls and the partition wall 5 of the chute are made of transparent material to facilitate the control of the movements of the sheets 68, 68a.

What I wish to secure by United States Letters Patent is:

1. In a typewriting machine having a paper carriage means for feeding at least one sheet in front of the platen said means comprising at least one rack, slidably mounted in the carriage, a gearing positively driven by said rack, spur wheels forming part of the gearing and engaging perforations of the sheet to be located, a spring acting on said rack, means to tension said spring, means to retain the rack against the action of said spring, means to release the rack and means to stop the rack at a predetermined position.

2. In a typewriting machine, as defined in claim 1, bars adapted to cooperate with the rack to release it and to arrest it in predetermined position, and a plurality of keys for operating said bars.

3. In a typewriting machine, the combination of a platen, a support for a sheet of paper adapted to retain the sheet in operative relation with respect to the platen, a spring controlled train of gears, a rotary feeding element in engagement with the sheet of paper and forming part of said spring controlled train of gears, means for locking the train of gears against movement, and means effective on the rotary feed element in engagement with the paper for releasing said spring controlled train of gears to the action of the spring for selectively determined rotation of the rotary feed element in engagement with the paper to advance it relatively to the platen over a selectively predetermined distance.

4. In a typewriting machine, the combination of a platen, a support for superimposed sheets of paper in front of the platen, said sheets of paper being movable relatively to each other, rotary feed elements, one in engagement with each sheet of paper, a train of gears connected with said rotary feed elements, a spring for operating said train of gears, and a plurality of severally operable key means for selectively determining the feed element to be operated, and

the extent of operation of said feed element selected.

5. In a typewriting machine, the combination of a platen, a support for a pair of sheets of paper in superimposed but spaced relation with respect to the platen, rotary feeding elements in engagement with said papers respectively, a pair of rack bars, springs for operating said rack bars, trains of gears interposed between said rack bars and said feeding elements respectively, and means accessible from a keyboard of the typewriting machine for selectively determining the movement of said rack bars under the action of their springs, and the movement of the feeding elements associated with said rack bars respectively.

6. In a typewriting machine, the combination of a platen, a support for a pair of sheets of paper in operative relation with respect to the platen, means for spacing said sheets of paper from each other, a pair of rotary feeding elements in engagement with said papers from opposite sides of the same, a pair of rack bars, springs for operating said rack bars, gear trains interposed between said rack bars and said rotary feed elements respectively, locking pawls for said rack bars, means for selectively releasing the locking pawls for said rack bars, and means independent of the selection of the releasing means for the locking pawls for limiting the movement of the released rack bar to drive the associated rotary feeding element for the sheet of paper to be advanced.

7. In a typewriting machine, the combination of a paper support adapted to retain a pair of sheets of paper in parallel superimposed but spaced relation from each other, rotary feeding elements in engagement with said sheets of paper respectively, a pair of rack bars, springs for operating said rack bars, sets of gearing interposed between said rack bars and said feeding elements respectively, said rack bars being provided with stops, locking pawls, means for normally maintaining the locking pawls in engagement with the rack bars, means accessible from the keyboard of the typewriting machine for selectively releasing one or the other locking pawl, bars supported in the machine for movement relatively to the rack bars, and key means for selectively moving any one of the plurality of bars into the path of movement of the stops on the rack bars.

8. In a typewriting machine, the combination of a support for a pair of sheets of paper in superimposed but spaced relation and in operative position with respect to the platen of the

machine, rotary feeding elements in engagement with the sheets of paper respectively, a pair of rack bars, springs for operating said rack bars, gear trains interposed between said rack bars, and said feeding elements respectively, whereby said feeding elements are actuated to the extent of movement of the associated rack bars, locking pawls for said rack bars, additional holding elements for maintaining the rack bars normally in a position in which the springs controlling them are under tension, a plurality of keys, and means interposed between the selectively operable keys and the rack bars for releasing the locking pawls of the rack bars, the additional holding elements for the rack bars and for stopping the rack bars after a selectively predetermined extent of movement of the same.

9. In a typewriting machine, the combination of a support for a pair of sheets of paper adapted to retain the sheets in superimposed but spaced relation and in operative position with respect to the platen of the machine, rotary feeding elements in permanent engagement with said sheets of paper respectively, rack bars, springs for operating said rack bars, trains of gears interposed between said rack bars and said rotary feeding elements, locking pawls for said rack bars, means for selectively releasing one or the other locking pawl from the rack bar with which it is associated, and means for imparting movement to a predetermined extent to the rack bar released from its locking pawl, whereby the feeding element associated with said rack bar acts on the pertaining sheet of paper to feed it a predetermined extent.

10. In a typewriting machine, the combination of a support for a pair of sheets of paper adapted to retain said papers in operative relation with respect to the platen and in superimposed but spaced relation with respect to each other, rotary feeding elements in engagement with said sheets of paper respectively, a pair of rack bars, springs for operating said rack bars, gear trains interposed between said rack bars and said feeding elements respectively, locking pawls for said rack bars and normally held in engagement with the same, said rack bars being provided with stops fixedly located thereon, a plurality of keys, a plurality of bars operable selectively from said keys and adapted upon operation of the keys to be projected into the path of the stop of either rack bar, and means for selectively releasing either locking pawl from said rack bar, said releasing means being independent of said keys.

PAUL HEGNAUER.
